United States Patent Office

Des. 177,384
Patented Apr. 10, 1956

177,384

FINGER RING OR THE LIKE

Adolph Katz, Providence, R. I., assignor to Coro, Inc.,
New York, N. Y., a corporation of New York

Application October 6, 1955, Serial No. 38,263

Term of patent 7 years

(Cl. D45—10)

Fig. 1

Fig. 2

Fig. 3

Fig. 1 is a plan view of a finger ring or the like showing my new design.

Fig. 2 is an edge view thereof.

Fig. 3 is a side view of Fig. 2.

I claim:

The ornamental design for a finger ring or the like, substantially as shown.
